[57]

ABSTRACT

A system of levers controls the main gas solenoid valve switch and ignition burner valve whereby depression of a starting push-button opens the ignition valve while keeping the switch closed, at the same time forcing the armature of a thermoelectric control device into engagement with the ignition flame sensitive magnet. After the interval required to activate the magnet, the push-button is retracted to close the switch and render the system operative subject to shutdown by release of the armature upon failure of the ignition flame. A shutdown push-button is also provided.

THERMOELECTRIC IGNITION SAFETY DEVICE

German Pat. No. 1 205 923 discloses a thermoelectric ignition safety device, in particular for circulation gas water heaters, in which a manually operated push-button acts on a pair of levers, joined in scissorslike manner, one of the levers returning into its initial position together with the push-button while the other lever is retained by the armature of a magnet which is thermoelectrically energized by the ignition flame heat to keep open a pilot gas valve and in which one of the levers supports a switch with a resiliently depressable switch pin for controlling the main gas valve, said switch pin being supported on the lever.

This scissors system functions so that the closing of the switch, that is to say opening of the main gas valve when the push-button is released, takes place only if the levers can be spread, that is to say if one of the levers is retained by the thermoelectrically energized magnet.

The improvement of a patent of addition of the said German patent (German application Pat. No. P 20 46 601.7) seeks to avoid the frictional forces which are present in the device of the parent patent between the armature and the switch in order to improve the response reliability of the thermoelectric ignition safety device. These forces, which inhibit the motion of the lever, also include the stiffness of the electric leads connected to the switch and passing through the wall of the casing, frequent flexure of such leads possibly causing fracture thereof.

According to the parent patent, the magnet armature with its control pin is disposed axially relative to the switch pin of the switch mounted on the switch housing to act only on said switch in the event of circumstances calling for safety action. Even if the pilot gas valve should fail to return into its closed position when the ignition flame is extinguished, the electric circuit of the main gas valve is still interrupted by the dropped out magnet armature and unburnt gas cannot escape from the main burner.

Since depressing the push-button and application of the armature to the magnet by means of the first lever accompanied by opening of the pilot gas valve through the second lever, simultaneously pivoted with the first lever, causes the switch pin of the switch for the ignition safety device to follow the armature pin and to close the electric circuit of the main gas valve, a further embodiment of the invention proposes that a second switch be connected electrically in series with the first switch, the second switch interrupting the electric circuit through the first lever of the pivoted pair of levers for as long as the push-button remains depressed. The first lever together with the push-button returns into its starting position and closes the circuit of the main gas valve to the second switch only when the magnet is sufficiently energized and retains the armature plate when the push-button returns so that the main gas valve releases gas to the burner. The relative position of the switches are such that the contact of the second switch is already open when the push-button is depressed before the first switch, for the safety system, closes the electric contact.

The object of the present invention is to provide a construction which, by contrast to the parent German Pat. No. 1 205 923, substantially avoids force deflections and accompanying disturbing frictional forces in

circumstances calling for the operation of the safety device and by contrast to the patent of addition utilizes only a single switch.

The invention therefore relates to a thermoelectric ignition safety device in which a manually operated push-button acts on a pair of levers, joined to each other in scissors configuration, one of the levers returning together with the push-button into its starting position while the other lever is retained against the action of a loading spring by the armature of a magnet which is thermoelectrically energized by the ignition flame heat and thus maintains a pilot gas valve in the open position, a switch fixed relative to the housing being provided, the switching pin of said switch being actuatable in the sense of opening said switch by means of a tappet which is joined to the armature and extends in parallel to the switching pin when the armature drops out under the effect of the loading spring, and comprising a system in which the tappet acts on a switch lever bearing on the switching pin, said lever being retained in a position which keeps the switching pin in the open position through a further lever arm when the push-button is depressed.

One embodiment of the invention is explained hereinbelow by reference to the accompanying drawings in which

FIG. 1 is a schematic view of the thermoelectric ignition safety device of the invention in inoperative state;

FIG. 2 is a schematic view showing the device in the switched-on state, and

FIG. 3 is a schematic view showing the device in the operative state.

An electromagnet 2, thermoelectrically energized in known manner when the ignition flame, not shown, is burning, is disposed in a housing 1. The armature 3 of the electromagnet 2 is guided so as to be axially slideable and, in a manner to be described hereinbelow, may be thrust by means of a push-button 4 against the poles of the electromagnet 2. The housing 1 also contains a pilot gas valve 5 whose valve plate 5' is biased by a valve closing spring 6. A rocker lever pair 7, 8, joined to each other in scissors configuration, is pivotably supported in common at 9 on the housing 1. The lever 7 is retained on the push-button 4 in its inoperative state by the restoring spring 10 of the push-button 4 via the pin 11.

The disc 12 is mounted on the push-button 4. It functions as an abutment for the spring 13. It acts via the sliding disc 14 and the lever arm 15' of the two-armed lever 15 in the opening sense on the switch pin 16' of the switch 16. The armature spring 17 acts in the same sense via the rod 18 on the lever arm 15'' of the lever 15. The spring bears on the housing 19 of the magnet 2 and thrusts the rod 18 against the lever arm 15'' via the disc 20, fixedly mounted on the rod 18. The extended position of the rod 18 is defined when the armature 3 bears on the housing 19 of the magnet 2. The spring 13 is weaker than the spring which biases the switch pin 16' of the switch. The off position of the switch 16 is defined by the armature spring 17.

One lever arm 8' of the lever 8 grips in bifurcated manner under the disc 20 while the second lever arm 8'' is disposed opposite to the rod 5' of the valve plate 5'. The end of the lever arm 8'' is also positioned opposite to the off push-button 21 which is retained by the restoring spring 22 in the stand-by position.

To place the safety device in operation, the push-button 4, see FIG. 2, is depressed against the force exerted by the restoring spring 10. At the same time the lever 7 is pivoted via the pin 11, thus causing the lever arm 7' to abut the armature 3 against the magnet 2 through the disc 20 and the rod 18. Furthermore, the lever arm 15' of the lever 15 is pivoted via the disc 12 and the spring 13 as well as the sliding disc 14, so that the switch 16 remains open although the rod 18 is separated from the lever arm 15''. The spring 13 is designed so that in the illustrated position it will overcome the force exerted by the switch. The residual spring travel of the spring is provided to accommodate the overrun of the push-button 4.

Furthermore, the lever 8 is rotated in the clockwise direction by virtue of the disc 20 and the lever arm 8' so that the lever arm 8'' moves the rod 5'' of the valve plate 5' against the force exerted by the valve closing spring 6 in the upward direction to open a passage for the ignition gas.

When the thermocouple has sufficiently energized the electromagnet 2 after ignition of the ignition or pilot flame, the armature 3 will be retained in known manner by the magnet so that the push-button 4 may be released. This produces the position illustrated in FIG. 3. The return of the push-button 4, performed the restoring spring 10, compels the lever 7 to follow through the pin 11 and causes the said lever to pivot back to its starting position. The lever arm 7' leaves its abutment position against the disc 20. The drop-out path of the armature plate 3 with the rod 18 is thus cleared for the event which gives rise to the need for the action of the safety system.

Retraction of the push-button 4 causes the spring 13 to relax so that because of the slight force exerted by it the lever 15 with its lever arm 15' is driven by the switch pin 16' through the spring force of the switch thus closing the electric circuit of the gas solenoid valve. The lever 8 remains in its position and maintains the pilot gas valve 5 in the open position through the lever arm 8''.

The circuit controlled by the switch may also be used to control the pump of a circulating heating system in which opening of the main gas valve depends on the circulating water. In addition it is possible for both the gas solenoid valve and the pump to be simultaneously controlled.

It is common practice to control a relay by means of a small capacity switch. The relay may be employed to control two or more circuits which are DC isolated, for example, in order to control the pump and the gas solenoid valve. However, this arrangement is too expensive because of the relay necessarily required for it. By using the ignition safety system described hereinabove it is however possible to control at least two circuits, DC isolated from each other, in a less expensive manner by disposing a second switch adjacent to the first switch so that both may be actuated by the lever 15. To this end it is merely necessary to allow for the fact that the force of the spring 13 must be adapted to the total force exerted by the two switches. Furthermore, the switching moments of the switches may be adjusted with respect to time relative to each other by means of a relative offset between the switches. If the last mentioned features were to be achieved by means of a relay this would result in further additional and substantial costs.

If the ignition flame is extinguished and the magnet releases the armature, the rod 18 will pivot the lever 15 so that the switch pin 16' interrupts the circuit. The valve closing spring 6 also causes the lever 8 to return into its position illustrated in FIG. 1 so that the passage of ignition gas is interrupted.

The control circuit controlled by the thermoelectric ignition safety device may be changed, if required, from the operative state into the inoperative state by 10 disposing adjacent to the push-button 4 for taking the thermoelectric safety device into operation, a second push-button by means of which the armature is forcibly detached from the magnet. The push-button 21 in the drawing is provided to this end, said push-button being 15 depressed against the force of the restoring spring 22 to detach the armature 3 from the magnet 2 via the lever arms 8'', 8'. The pilot gas valve 5 is closed by the valve closing spring 6. After the push-button 21 is released, the spring 22 returns same into the starting position.

I claim:

1. Thermoelectric ignition safety device in which a manually operated push-button acts on a pair of levers, joined to each other in scissors configuration, one of the levers returning together with the push-button into its starting position while the other lever is retained against the action of a loading spring by the armature of a magnet which is thermoelectrically energized by the ignition flame heat and thus maintains a pilot gas valve in the open position, a switch fixed relative to the housing being provided, the switching pin of said switch being actuatable in the sense of opening said switch by means of a tappet joined to the armature and extending in parallel to the switching pin when the armature drops out under the effect of the loading spring, characterized in that a tappet (18) acts on a switch lever (15) bearing on the switching pin (16') said lever (15) being retained in a position which keeps the switching pin (16') in the open position through a further lever arm (15') of said lever (15) when the push-button (4) is depressed.

2. Thermoelectric ignition safety device according to claim 1, characterized in that the levers (7, 8), joined to each other in scissors configuration, are constructed as rocker levers, the direction of motion of the manually operated push-button (4) and of the pilot gas valve (5) extending perpendicularly to the direction of motion of the armature (3) and of the rod (18) and of the switch pin (16').

3. Thermoelectric ignition safety device according to claim 1, characterized in that the push-button (4) acts on the aforementioned further lever arm (15') of the switch lever (15) through a spring (13) which is stressed when the push-button (4) is depressed and whose spring stress then overcomes a spring force which normally maintains the switch pin (16') and the switch (16) in the closed position.

4. Thermoelectric ignition safety device according to claim 1, characterized in that a shutdown push-button is provided which acts on the lever (8) associated with the lever pair in opposition to the retaining force of the magnet (2) of the armature (3).

5. Thermoelectric ignition safety device according to claim 2, characterized in that the push-button (4) acts on the aforementioned further lever arm (15') of the switch lever (15) through a spring (13) which is stressed when the push-button (4) is depressed and

whose spring stress then overcomes a spring force which normally maintains the switch pin (16') and the switch (16) in the closed position.

6. In a gas ignition safety device including a spring loaded normally closed main valve solenoid control switch, a spring loaded normally closed ignition burner gas valve, a thermoelectric device having a magnet sensitized by the heat from the ignition flame and an armature controlled by said magnet, a spring loaded normally retracted starting push-button having a shaft, and means for the safety control of said switch and ignition gas valve, the improvement wherein said means comprises a pivotally mounted switch control lever having a first arm in control engagement with the solenoid valve switch and an extension of said arm adapted to engage said armature, said lever having a second arm in operative engagement with said push-button shaft, a pivotally mounted ignition valve control lever having a first arm in control engagement with said valve and a second arm connected with said armature for movement therewith, and a pivotally mounted starting lever

having a first arm connected to said push-button shaft for movement therewith and a second arm arranged to push said armature toward said magnet, the arrangement being such that depression of said push-button holds said switch open through said switch control lever, pushes said armature into engagement with said magnet through said starting lever and opens said ignition valve through said ignition valve control lever for an interval sufficient for the ignition flame to activate said magnet and hold said armature in operating position whereafter retraction of said push-button permits retraction of said switch control lever to allow said switch to open and retraction of said starting lever.

7. Structure in accordance with claim 6 and including a spring loaded normally retracted shutdown push-button having a shaft adapted to engage said first arm of said ignition valve control lever whereby depression of said shutdown push-button closes said ignition burner valve and simultaneously detaches said armature from said magnet.
